UNITED STATES PATENT OFFICE.

GEORGE BARRALL, OF NANTICOKE, PENNSYLVANIA, ASSIGNOR OF ONE-HALF TO
JAMES E. BERGIN, OF NANTICOKE, PENNSYLVANIA.

WRENCH.

1,279,827.

Specification of Letters Patent.

Patented Sept. 24, 1918.

Application filed April 12, 1918. Serial No. 228,151.

To all whom it may concern:

Be it known that I, GEORGE BARRALL, a citizen of the United States, residing at Nanticoke, in the county of Luzerne and State 5 of Pennsylvania, have invented a new and useful Wrench, of which the following is a specification.

This invention relates to pipe wrenches, one of its objects being to provide a wrench 10 of this type utilizing a chain so arranged that the wrench can be adjusted readily to pipes of different sizes.

Another object is to provide a wrench 15 of this character having simple and efficient means for adjustably connecting one end portion of the chain to the head of the wrench.

A still further object is to provide a novel 20 arrangement of eccentrics whereby a quick take up of slack in the chain will occur when the wrench is moved to turn the engaged pipe, thus reducing to the minimum the lost motion which has heretofore been present in pipe wrenches of the chain type.

25 A further object is to provide a wrench which will not indent or crush the pipe engaged thereby but which has a jaw of novel form which will engage the pipe at several points, thus to distribute the pressure 30 thereon.

With the foregoing and other objects in view which will appear as the description proceeds, the invention consists of certain 35 novel details of construction and combinations of parts which will be hereinafter more fully described and pointed out in the claim, it being understood that various changes may be made in the construction and arrangement of the parts without departing 40 from the spirit or sacrificing any of the advantages of the invention as set forth in the appended claim.

In the accompanying drawings the preferred form of the invention has been 45 shown.

In said drawings—

Figure 1 is a side elevation of the wrench. Fig. 2 is a section on line 2—2, Fig. 1.

Fig. 3 is a section on line 3—3, Fig. 1.

50 Referring to the figures by characters of reference, 1 designates the shank or handle of the wrench one end of which is extended between side plates 2 which are held to the shank by rivets or the like and are provided 55 on their inner faces with shoulders 3 de-

signed to fit snugly against the back and end faces of the shank 1. The plates 2 are extended past and beyond the front face of the shank to form ears 4 which are thickened as shown and which are provided, in their 60 inner faces, with recesses 5.

Each of the side plates 2 has an extension 6 projecting beyond the end of the shank, said extension having a curved edge constituting a continuation of the front edge of 65 the plate 2 to constitute an eccentric bearing portion, indicated at 7.

A jaw which, in the present instance is made up of three plates 8, is connected to the extensions 6 by means of a rivet 9 or 70 the like, one of the plates being extended between the extensions while the other plates lap the outer faces of said extensions, as shown particularly in Fig. 2. Each of the plates 8 has a recess 10 in one edge the walls 75 of which are stepped as shown in Fig. 1, thus to provide shoulders for engaging the pipe or other article to be gripped.

Pivottally connected to the plates 8 is one 80 end of a chain 11 and the pins which connect the links of the chain are extended laterally to form stop lugs 12. The distance between the ears 4 is such as to allow the chain 11 to enter snugly therebetween and when so positioned the lugs 12 at one end 85 of the link between the ears will enter the recesses 5, as shown in Fig. 3, thus to anchor the chain to the plates 2.

In using the wrench herein described the chain is drawn tightly around the pipe or 90 other object to be turned and is then positioned between the ears 4 with lugs 12 on one of the links seated within the recesses 5. By then swinging the shank or handle 1 in the direction of the arrow in Fig. 1 the 95 eccentric edges 7 will engage and form take up bearings for the links adjacent thereto while the plates 2 are swinging on the pivotal connection 9. This will take up any slack in the chain and cause the chain to 100 quickly and firmly engage the pipe or other object, P, forcing the shoulders in recess 10 into engagement with the said object and so hugging the said object that it will be held without crushing or indentation.

The plates 2 can be removed and others substituted therefor should the plates become worn or be otherwise rendered unfit for use. Thus the handle or shank can be used without change, this being a consider- 110

able saving of metal, particularly in a large size tool.

What is claimed is:—

A pipe wrench including a shank or handle, side plates secured thereto and having spaced ears provided in their inner faces with recesses, said plates having end extensions, said extensions and plates forming eccentric bearing edges, plates pivotally connected to and extending between and to opposite sides of the extensions and coöperating to form a jaw, said plates having recesses in one edge provided with stepped

walls, and a chain connected at one end to the jaw and insertible between the ears, said chain having laterally extending lugs insertible into the recesses in the ears, the eccentric edges constituting take up bearings for the chain.

In testimony that I claim the foregoing as my own, I have hereto affixed my signature in the presence of two witnesses.

GEORGE BARRALL.
